[57] CLAIM

The ornamental design for an airplane, substantially as
shown and described.

DESCRIPTION

FIG. 1 is a top plan view of an airplane showing my
new design, the bottom being plane and unornamented;
FIG. 2 is a side elevational view of FIG. 1, the other
side being identical;

FIG. 3 is a front elevational view of FIG. 1;

FIG. 4 is a rear elevational view of FIG. 1;

FIG. 5 is a side elevational view similar to FIG. 2, but
with the engines in an alternate position; and
FIG. 6 is a front elevational view of FIG. 5.

FIG. 1

FIG. 2

FIG. 4

FIG. 3

FIG. 6

FIG. 5
